UNITED STATES PATENT OFFICE.

ELAM V. BENTLEY, OF EVERETT, WASHINGTON.

COMBINED HEATER AND RADIATOR.

971,347.

Specification of Letters Patent. Patented Sept. 27, 1910.

Application filed February 3, 1909. Serial No. 475,752.

To all whom it may concern:

Be it known that I, ELAM V. BENTLEY, a citizen of the United States, and a resident of Everett, in the county of Snohomish and State of Washington, have invented a new and Improved Combined Heater and Radiator, of which the following is a full, clear, and exact description.

The purpose of this invention is to provide novel details of construction for a heat radiating stove that may be readily converted into a cooking stove, the device being well adapted for consuming liquid fuel or coal by slight changes in construction.

15 The invention consists in the novel construction and combination of parts, as is hereinafter described and defined in the appended claim.

Reference is to be had to the accompanying drawings forming a part of this specification, in which similar characters of reference indicate corresponding parts in all the views.

Figure 1 is a side elevation of the device arranged as a heat radiator; Fig. 2 is a sectional side view, taken through the longitudinal center of the heat radiator shown in Fig. 1; and Fig. 3 is a transverse sectional view, substantially on the line 3—3 in Fig. 2.

30 In carrying into effect the features of the invention, any available material may be utilized, and the shape thereof may be considerably modified within the scope of the invention. In the example here presented, 35 plate metal is employed, which is preferably cut and bent into form as represented in the drawings, which will now be described.

The preferred fuel for the evolution of heat, is liquid, such as kerosene, gasoline or 40 alcohol, which may be consumed in a suitable burner fed by a wick, that is supplied with said combustible from a reservoir.

In the drawings, 10 indicates a liquid holder, that is cylindrical and may be of any 45 preferred dimensions, said holder or tank having a filler orifice in its upper side, normally closed with a screw cap α or equivalent means.

50 There are a plurality of burner tubes b projected from the upper side of the tank 10, that contain wicking c , as indicated in Fig. 3, said tubes being spaced from each other; and as represented, the wicks may be adjusted in the usual manner by thumb 55 wheels d on the ends of shafts d' that enter the side of the tank, and as this is a com-

mon means for regulating the height of the wicks, it is not considered necessary to further illustrate this minor detail.

The tank 10 is supported concentrically 60 within a cylindrical wall 11, which is the base section of the combined heater and radiator. Upon the upper edge of the base section 11, a top wall 12 therefor is detachably mounted and removably secured by 65 means of a depending peripheral flange 12^a, that is secured upon the edge of the top wall and fits loosely upon the exterior surface of the base section when the top wall is mounted thereon. Centrally in the top wall 70 12, a circular opening is formed wherein is fitted and secured the lower edge of a deflector cone 12^b, that projects upward through said opening. There is an upwardly projecting peripheral flange e 75 formed on the edge of the top wall 12, and may be integral with the flange 12^a, said flange e serving to hold in place a coacting second section that is constructed as follows.

A plate metal coniform wall 13, that at 80 its lower end is provided with an inwardly turned flange, has such a relative diameter at said lower end as adapts it to fit loosely within the upturned peripheral flange e when the flange on the wall 13 is seated 85 upon the top wall 12. It will be seen in Fig. 2 that there is an annular space or channel h formed between the central cone 12^b and the coniform wall 13, when the latter is in position on the top wall 12; and 90 furthermore, that the burners b are so relatively positioned that flame therefrom will impinge upon the inner surface of the coniform wall 13 and spread thereover and quickly heat said wall, that converges the 95 annular heat current as it passes upward.

Coöperative with the base section 11 and coniform section 13, is a third section, comprising the following details: Upon the lower edge of an inverted coniform wall 14, 100 that is formed of plate metal, is affixed the upper edge of a circular downwardly flaring wall 14^a, these firmly connected walls being held so as to give the lowermost wall 14^a a central position in the annular space h , 105 by angular braces i , that are respectively secured upon the inverted coniform wall 14 near its lower end and the upper portion of the coniform section 13, as is indicated in Fig. 1.

A downwardly converging deflector cone 15, is centrally and vertically supported and

secured in the inverted coniform wall 14, by an impingement of its lower end as at *m*, upon the apex of the deflector cone 12^c, and securing U-shaped braces *n* between the inverted coniform wall 14 and the deflector cone 15 near their upper ends. The upper end of the deflector cone 15 may be closed, as shown at 15^a, and on said top wall a handle piece *o* is secured, which affords means for placing the third section in position on the top wall 12^a or removing it therefrom.

It will be noted in Fig. 2 that the relative positions given to the opposed deflector cones 12^b and 15, and the coniform walls 14 and 14^a that have a common axis, when the third section is in position on the top wall 12, affords an annular centrally converged air passage *p* between the cones and concentric walls 14, 14^a, which passage extends from the top wall 15^a to the lower end of the flaring wall 14^a, which end is spaced from the top wall 12 so as to permit an air passage *r* therebetween.

In the operation of the apparatus hereinbefore described, assuming that liquid fuel in sufficient amount has been placed in the tank 10 and the wicks *c* are lighted, the flame therefrom will impinge upon the inner surface of the coniform wall 13 and trend upward through the annular channel *h*, the evolved heat current enveloping the outer surface of the depending converged wall 14. This heat current will create a partial vacuum in the inner annular air passage *p*, which will induce a downward air current therethrough, this air current becoming highly heated by its intimate contact with the flames from the wicks *c*, and it will be noted that the rarefied and hot air that impinges upon the wall 14, will be deflected therefrom into surrounding space and warm the air therein.

It is claimed that the details of construc-

tion for a combined heater and radiator 45 herein set forth, are coöperative and afford a compact, inexpensive, and practical apparatus for the purpose specified.

It will be evident from the description, that applicant's radiating means comprises 50 a pair of spaced concentric frusto conical rings, a second pair of spaced concentric frusto conical rings arranged above the first named rings and with their apexes downward, the outermost ring being provided 55 with a petticoat extending between the first named rings.

Having thus described my invention, I claim as new and desire to secure by Letters Patent:

In combination, a liquid fuel supply tank, burners thereon, a casing surrounding the tank, a top wall on the casing having an upright peripheral flange thereon, and also having a central conical deflector, an inverted conical deflector vertically supported on the apex of the first-mentioned conical deflector, an upwardly converged coniform wall, a downwardly converged coniform wall mounted upon the first-mentioned wall 70 and secured to the inverted conical deflector, said converged walls being spaced from the cone deflectors and affording an annular air passage therebetween, and an upwardly converged coniform wall seated upon the top 75 wall of the casing and spaced from the first named upwardly converged coniform wall, affording a conduit for the heat current from the burners, which current envelops and heats the upper inverted coniform wall, 80 from which the heat is radiated.

In testimony whereof I have signed my name to this specification in the presence of two subscribing witnesses.

ELAM V. BENTLEY.
